UNITED STATES PATENT OFFICE

EUGENE C. TURNER, OF SAN DIEGO, CALIFORNIA

COMBINATION BOLT AND HASP

Application filed February 14, 1924. Serial No. 692,786.

My invention relates to a combination bolt and hasp, particularly adapted for securing a door, window, gate or the like at one side, and the objects of my invention are: First, to provide a combination bolt and hasp for securing the one side of doors, windows, gates and the like; second, to provide a device of this class which will support the free side of a door, gate or the like rigidly and prevent its being moved back and forth; third, to provide a device of this class in which the free sides of double doors may be rigidly secured together and prevent their swinging back and forth; fourth, to provide a bolt for bolting a door with a staple to be used in connection with a hasp for securing the free sides of doors and the like; fifth, to provide a device of this class whereby a bolt with a staple is movable, thereby providing for movement 20 of the staple to which the hasp is secured, thus providing for a fit at all times after shrinkage of doors and the like; sixth, to provide a device of this class in which the bolt may be used and the lock locked in the staple in the bolt 25 when it is not desired to lock the door, so that the lock is always in position when desired for use; seventh, to provide a device of this class in which the screws for supporting both the hasp and the bolt are covered when the 30 door is locked so that the screws cannot be readily removed; eighth, to provide novel means for latching and locking doors, and ninth, to provide a device of this class which is simple and economical of construction, 35 durable, easy to operate, applicable for use in connection with all classes of doors, gates and the like, and which will not readily deteriorate or get out of order.

With these and other objects in view, as 40 will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a front elevational view of my 45 device in its preferred form, shown in connec-

tion with a door A and wall B, showing the bolt in inoperative position and the hasp open, so that the door may be readily opened; Fig. 2 is a top view of the same, showing the bolt in operative position and the hasp in position to be locked; Fig. 3 is a transverse sectional view through 3-3 of Fig. 2; Fig. 4 is a view similar to that of Fig. 1 in a slightly modified form; Fig. 5 is a view similar to that of Fig. 2 in the same slightly modified form as that of Fig. 4, and Fig. 6 is a transverse sectional view through 6-6 of Fig. 5.

Like characters of reference refer to similar parts and portions throughout the several views of the drawings.

The bolt member 1, staple or loop member 2, bolt support 3, screws 4, hasp member 5, hasp member 6, pin 7, and hasp screws 8, constitute the principal parts and portions of my device in its preferred form.

The bolt support 3 is a loop-shaped member made out of metal plate and the edges spaced a short distance apart at 3^b, Fig. 3. It is provided with a plurality of holes 3^a and 3^c, the holes 3^a in the normally outer portion and the holes 3^c in the inner flanged portion. The holes 3^c are counter-sunk, adapted for the heads of the screws 4, so that their upper surfaces fit in flush with the inner surfaces of the flanges of the member 3. This support 3 is secured to the jamb side of the wall B by means of the screws 4, the bolt 1 being provided with holes 1^a conforming to the holes in the member 3 to permit the screws to pass therethrough when said members are in certain relative positions to each other. This bolt member 1 is adapted to reciprocate in the loop portion of the member 3 and it is provided with a staple or loop member 2 rigidly secured therein, preferably by riveting, the space 3^b providing space for riveting the same. This staple 2 extends out through a longitudinal slot 3^d in the member 3, considerably longer than the staple 2, thus providing means for permitting the movement 95 of the bolt 1 in the support 3 past the side of the door A. Secured to the door in alignment with the support 3 and bolt 1 is the hasp member 5 by means of screws 8 and pivotally connected to this member 5 is another hasp mem-

ber 6 by means of the pin 7. This hasp member 6 is provided with a slot 6^a therein adapted to pass over the staple 2 when the staple 2 is moved into the proper relative position thereto, as shown best in Fig. 2 of the drawings, after which a padlock may be placed through the staple and the door securely locked. However, if it is not desired to lock the door but to secure it without locking, the hasp may be left open, as shown in Fig. 1, and the bolt moved so that its end extends over the door against the member 5, and the door is held in position while the padlock may be locked in the staple 2 ready for use when required.

In the modified form of construction, shown in Figs. 4, 5 and 6, the members 1, 2 and 3 are the same as that in Figs. 1, 2 and 3 and the hasp member 6 and pin 7 are the same. However, the hasp member 5 in this case is provided with overturned flanges 5^a, shown best in Fig. 6, and between these flanges and the main body portion the extended end of the bolt 1 is adapted to reciprocate, thus forming a keeper or rigid support for the end of the bolt member 1 when the bolt is positioned over the hasp member 5. It is preferred in this modified form of construction to place the hasp on the jamb side of the wall and the bolt and support on the door in the reverse order to that in Figs. 1, 2 and 3, where the device is used in connection with a single door construction.

Though I have shown and described a particular construction, combination and arrangement of parts and portions and a certain modification thereof, I do not wish to be limited to this particular construction, combination and arrangement nor to the modification, but desire to include in the scope of my invention the construction, combination and arrangement substantially as set forth in the appended claims.

Having thus described my invention, what I claim as new and desire to secure by Letters Patent, is:

1. In a combination bolt and hasp for the free side of doors, a slidably mounted bolt member adapted to be shifted over the joint between the free side of doors and provided with a staple, and a foldable hasp member mounted adjacent thereto provided with a slot therein and adapted to extend over said staple member, when it is shifted over said joint.

2. In a device of the class described, a bolt support provided with a slot in one side extending its full length and a slot in its opposite side extending over a portion of said support longitudinally therein and provided with a loop member in the one side thereof extending through said last mentioned slot, and a hasp member adapted to engage said loop member when said loop member is moved to operative position in said slot relatively

to said hasp member, said bolt support and bolt being provided with conforming holes adapted to admit screws when said bolt is in inoperative relative position to said hasp member, but nonconforming when said bolt is moved out of such position. 70

3. In a combination bolt and hasp for the free side of doors, a bolt support provided with a slot in one side extending over a portion only of said support and longitudinally therein, a bolt extendible over the free side of the door provided with a loop member in one side thereof extending through said slot, and a hasp member adapted to engage said loop member when said loop member is moved to operative position in said slot relatively to said hasp member. 75

4. In a combination bolt and hasp for the free side of doors, a bolt support provided with a slot in one side extending over a portion only of said support and longitudinally therein, a bolt extendible over the free side of the door provided with a loop member in one side thereof extending through said slot, and a hasp member adapted to engage said loop member when said loop member is moved to operative position in said slot relatively to said hasp member, said bolt support and bolt being provided with conforming holes adapted to admit screws when said bolt is 80 in proper relative position to said hasp member and nonconforming when said bolt is moved out of such position. 85

5. In a combination door-locking bolt and hasp for the free side of doors, a slidably mounted bolt member adapted to be longitudinally shifted across the joint between the free side of the door and the door jamb, said bolt having a loop at its outer side and intermediate its ends and a hasp shiftably mounted adjacent thereto and adapted to fit over the same, said hasp being provided with a slot therein adapted to receive said loop. 90

6. In a combination door-locking bolt and hasp for the free side of doors, a bolt support provided with a longitudinal slot therein, said slot extending over a portion only of said support, a bolt shiftably mounted in said support and extendible across the joint between the free side of the door and the door jamb, said bolt having a loop at its outer side and intermediate its ends, said loop extending through said slot, and a shiftably mounted hasp member adapted to engage said loop when the latter is moved to its operative position in said slot relative to said hasp member with the bolt over said joint. 115

In testimony whereof, I have hereunto set my hand at San Diego, California, this 2nd day of February, 1924. 125

EUGENE C. TURNER.
